UNITED STATES PATENT OFFICE.

SAMUEL R. BAILEY, OF AMESBURY, MASSACHUSETTS.

DESIGN FOR A CARRIAGE-SEAT.

SPECIFICATION forming part of Design No. 27,872, dated November 16, 1897.

Application filed August 5, 1897. Serial No. 647,261. Term of patent 3½ years.

To all whom it may concern:

Be it known that I, SAMUEL R. BAILEY, a citizen of the United States, residing at Amesbury, in the county of Essex and State of Massachusetts, have invented and produced a new and original Design for Carriage-Seats; and I do declare the following to be a full, clear, and exact description of the same, reference being had to the accompanying drawings, forming a part thereof.

Figure 1 is a plan view of a carriage-seat showing my new design. Fig. 2 is a sectional view taken in the line 2 2 of Fig. 1; and Fig. 3 is a cross-section on the line 3 3, shown in Fig. 1.

Similar letters refer to similar parts wherever they occur on the different parts of the drawings.

In the drawings, A represents the seat-frame, B the seat-rail, and C the back of a carriage-seat.

D D are the spindles extending from the seat-frame A to the seat-rail B.

The leading or material feature of my design consists of a spindle D, curved in an ogee ²⁵ form, and a curved backboard C above such spindles, as shown in the drawings, thus imparting a graceful and highly ornamental appearance to the carriage-seat.

Having described my invention, what I claim as new, and desire to secure by Letters Patent, is—

The design for a carriage-seat as herein shown and described.

In testimony whereof I have affixed my signature in presence of two witnesses.

SAMUEL R. BAILEY.

Witnesses:

ALBAN ANDRÉN,
LAURITZ N. MÖLLER.
